UNITED STATES PATENT OFFICE.

HARRY CROSS AND GEORGE J. GRIFFITHS, OF WOODSTOCK, ILLINOIS, ASSIGNEES TO THE OLIVER TYPEWRITER COMPANY, OF CHICAGO, ILLINOIS, A CORPORATION OF ILLINOIS.

DESIGN FOR A TYPE-WRITER BASE-FRAME.

No. 38,928.

Specification for Design.

Patented Dec. 3, 1907.

Application filed October 26, 1906. Serial No. 340,783. Term of patent 14 years.

To all whom it may concern:

Be it known that we, HARRY CROSS and GEORGE J. GRIFFITHS, citizens of the United States, residing at Woodstock, in the county of McHenry, in the State of Illinois, have invented a new and ornamental Design for Type-Writer Base-Frames, of which the following is a specification, reference being had to the accompanying drawing, forming a part thereof.

The figure is a perspective view of a

typewriter base frame showing our new design.

We claim:

The ornamental design for a typewriter base frame as shown.

HARRY CROSS.
GEORGE J. GRIFFITHS.
